UNITED STATES PATENT OFFICE.

AUGUST G. LIEBMANN, OF CHICAGO, ILLINOIS.

RAIL-CHAIR.

1,279,725.

Specification of Letters Patent. Patented Sept. 24, 1918.

Application filed January 11, 1916, Serial No. 71,583. Renewed June 13, 1918. Serial No. 239,876.

To all whom it may concern:

Be it known that I, AUGUST G. LIEBMANN, a citizen of the United States, residing at Chicago, in the county of Cook and 5 State of Illinois, have invented certain new and useful Improvements in Rail-Chairs, of which the following is a specification.

This invention relates to railway track appliances and more particularly to rail 10 chairs.

The object of the invention, generally stated, is to provide means for holding rails under all conditions of track and to provide for adjustment of said rails for both surface 15 and gage without disturbing the primary fastening devices.

A further object of the invention is to provide a rail chair particularly adapted for use on semi-hard wood ties and which will 20 effectually prevent creeping of the rails without the employment of the usual rail anchors.

A further object is to provide a rail chair, the bed plate of which is of rolled shape and 25 provided with angular openings which register with correspondingly shaped socket members in the cross tie for the reception of the rail clamping members.

A still further object is generally to improve the construction of the rail clamping members, whereby a more efficient and positive holding means for the rails is provided.

In the drawings:

Figure 1 is a perspective view of a rail 35 chair embodying the present invention;

Fig. 2 is an end elevation, one of the rail clamping members and its associated parts being shown in section;

Fig. 3 is a top plan view of Fig. 1;

Fig. 4 is a bottom plan view of the bed plate;

Fig. 5 is a bottom plan view of one of the rail clamping members detached;

Fig. 6 is a side elevation of Fig. 5;

Fig. 7 is a side elevation of one of the screw caps detached;

Fig. 8 is a top plan view of one of the guiding members or sockets for insertion in a cross tie;

Fig. 9 is a vertical sectional view of Fig. 8;

Fig. 10 is a side elevation of one of the clamping nuts used on the primary fastening device or bolt;

Fig. 11 is a top plan view of Fig. 10.

Corresponding and like parts are referred to in the following description and indicated in all the views of the drawings by the same reference characters.

Referring to the drawings, A represents 60 a rail having a standard cross section, and B the tie supporting the rail. Mounted upon the cross tie B is a bed plate 5 preferably a rolled shape, although the plate may be otherwise formed, if desired. The bed plate 65 5 is substantially rectangular in shape and preferably extends the entire width of the upper surface of the tie, said plate having its opposite ends provided with upstanding abutments 6, the inner faces 7 of which are 70 perpendicular to the upper surface of the bed plate, as shown. The lower face of the bed plate 5 is preferably formed with a series of transversely extending substantially elliptical depressions 8 which serve to lighten the 75 weight of the plate and also form in effect pockets which serve to receive the fiber of the wood when the bed plate is clamped in position on a cross tie. The bed plate 5 is provided with spaced openings 9 disposed 80 in staggered relation to the base flange of the rail and preferably octagonal in outline, said openings being adapted to register with openings 10 formed in the upper surface of the cross tie. Seated in the openings 10 in 85 the cross tie are detachable sockets or guiding members 11. The exterior walls of the socket members 11 are cylindrical, while the interior walls thereof are provided with a plurality of angular faces 12, preferably 90 eight in number, to correspond with the angular faces of the openings 9. The upper end of each socket member 11 opens through the upper surface of the cross tie, while the bottom thereof is provided with an opening 95 13 adapted to receive a primary fastening device, preferably in the form of a bolt 14. The upper end of each bolt 14 is preferably conical, as indicated at 15, and provided with threads 16 which engage a clamping nut 17, 100 this clamping nut 17, by engagement with the bottom of the adjacent member 11, serving to hold the socket member on the cross tie. Each clamping nut 17 is provided with recesses or notches 18 adapted to receive a 105 socket wrench and thus facilitate screwing the clamping nut home. If desired, however, the clamping nut 17, instead of being formed with the notches 18, may be provided with upstanding teeth. The bolts or primary 110

fastening devices 14 preferably extend entirely through the tie and are provided with terminal heads, not shown, which bear against suitable washers on the lower face 5 of the tie.

- As a means for holding the rail A in different positions of lateral and vertical adjustment on the bed plate, there are provided interchangeable rail clamping members 19 10 each preferably octagonal in shape and provided with an eccentric portion 20 having a plurality of angular faces 21 adapted to bear against the adjacent longitudinal edge of the base flange of the rail for shifting the 15 rail laterally with respect to the bed plate when the clamping members are adjusted, said eccentric portion defining a circumferential clamping lip 22 for contact with the upper face of the base flange of the rail, 20 as shown. Depending from the eccentric portion 20 of each rail clamping member is a sleeve or extension 23 having a cylindrical bore 24 and a plurality of exterior flat faces 25 corresponding in number to and adapted 25 to bear against the flat faces 12 of the socket members 11. The head of each rail clamping member is in the form of a flange 26 having a plurality of flat locking faces 27 adapted to bear against the inner face 7 of 30 the adjacent abutment for preventing accidental rotation of the rail clamping members after being once adjusted. The upper surface of the flange 27 of each clamping member is preferably formed with a plurality 35 of radiating reinforcing ribs 28 which merge into an upstanding flange 29 surrounding the bore 24, the upper surface of the upstanding flange 29 being provided with a flat face which forms a seat for a 40 spring washer 30.
- As a means for locking the rail clamping members in contact with the base flange of the rail A, there are provided suitable screw caps 31, each provided with a depending cylindrical portion having internal threads for 45 engagement with the threads 16 of the adjacent primary fastening device or bolt 14, the exterior walls of the cylindrical portions of the screw caps being smooth and unobstructed for engagement with the correspondingly smooth cylindrical walls 24 of the rail clamping members. The upper end of each screw cap is provided with an angular head 32 to permit the screw cap to be 50 conveniently grasped with a wrench or other suitable tool in adjusting the parts. The washers 30 insure the desired compensation for recoil of the rails under stress and at the same time keep the parts tight. 55
- It will here be noted that the rail clamping members 19 are disposed in staggered relation on the bed plate, while the bolts 14 not only serve to hold the socket members 11 on the cross tie but by engagement with 60 the threaded walls of the screw caps serve

to lock the rail clamping members in contact with the base flange of the rail. In order to assist in anchoring the bed plate on a cross tie, said bed plate is preferably formed with openings adapted to receive 70 screw spikes or bolts 33, one of these screw spikes or bolts being preferably arranged opposite each rail clamping member. Attention is here called to the fact that by reason of the length of the extensions 23 of the 75 rail clamping members, and the disposition of the socket members 11 with respect to the upper surface of the cross tie, an increased range of vertical adjustment of the rail clamping members may be effected without 80 the necessity of materially increasing the size or bulk of the rail clamping members.

In order to adjust the rail laterally on the bed plate for gage, it is merely necessary to remove the screw caps 31 and position one 85 of the rail clamping members within the adjacent socket member 11 with one of the angular faces of the large portion of the eccentric bearing against the base flange of the rail on one side thereof and with one 90 of the angular faces of the short portion of the eccentric of the other clamping member bearing against the base flange of the rail on the other side of said rail, after which the screw caps are threaded on the bolts 14 and 95 adjusted home which clamps the members 19 in engagement with the base flange of the rail and effectively prevents accidental displacement of said rail. It will be understood that by moving the rail clamping members 19 to different positions of adjustment within the angular openings 9 of the bed plate and socket members 11, the rail may be shifted laterally in either direction for gage, as required. In order to adjust the rail vertically for surface, the screw caps are rotated to elevate the same and a shim 34 placed beneath the rail, after which the screw caps are tightened, as best shown in Fig. 2 of the drawings. It will here be 100 noted that when the clamping members are adjusted, one of the flat faces of the eccentric of each clamping member is always in contact with the base flange of the rail, while one of the flat faces of the flange 26 105 of each clamping member is always in contact with the adjacent abutment so as to form an effective lock and thus positively prevent accidental rotation of the clamping members with respect to the bed plate. The 110 extensions 23 of the rail clamping members not only permit vertical adjustment of said rail clamping members, when shimming the rail for surface, but by reason of the engagement of the angular walls of the extensions 23 with the angular walls of the socket members 11 serve as an auxiliary means for preventing accidental rotation of the rail clamping members. The socket members 11 being detachable may be readily 115

applied to the cross ties at the treating plant and are held against displacement during shipment by the clamping nuts 17. By making the socket members 11 separate, the base plate of the chair may be readily rolled, thereby materially reducing the cost of manufacture.

From the foregoing description, it will be seen that the improved chair provides for 10 gage variations on curves and tangents, positively prevents creeping of the rails without the employment of rail anchors and provides for the restoration of gage without respiking and for rail surface variations and 15 the like without respiking.

Having thus described the invention, what is claimed as new is:

1. A rail chair including a bed plate having upstanding abutments and provided 20 with openings, the walls of which are angular, and rail clamping members engaging said abutments and provided with depending angular portions fitting within and movable to different positions around the 25 angular walls of the openings in the bed plate.

2. A rail chair including a bed plate having upstanding abutments and provided with openings, the walls of which are angular, and rail clamping members having angular faces adapted to engage said abutments 30 and provided with depending angular portions fitting within and movable to different positions around the angular walls of the 35 openings in the bed plate.

3. A rail chair including a bed plate having upstanding abutments and provided with openings, the walls of which are angular, and rail clamping members having angular faces for contact with the abutments and provided with eccentrics having angular faces for contact with the base flange of 40 a rail, said rail clamping member being provided with depending angular portions fitting within and movable to different positions around the angular walls of the 45 openings in the bed plate for holding the rail in different positions of lateral and vertical adjustment with respect to the bed plate.

5. A rail chair including a bed plate having upstanding abutments and provided with openings, the walls of which are angular, primary fastening devices, rail clamping members having angular faces for engagement 50 with the abutments and provided with depending angular portions fitting within and movable to different positions around the angular walls of the openings in the bed plate, and secondary fastening devices engaging the primary fastening devices and co-acting with the rail clamping members.

6. A rail chair including a bed plate having upstanding abutments and provided with openings, the walls of which are angular, socket members arranged beneath the

openings in the bed plate and adapted to fit in a cross tie, and rail clamping members having angular faces for engagement with the upstanding abutments and provided with depending angular portions extending 70 through the openings in the bed plate and into the socket members, said rail clamping members being movable to different positions around the angular walls of the openings in the bed plate for holding a rail in 75 different positions of lateral and vertical adjustment with respect to the bed plate.

6. The combination with a cross tie having spaced recesses formed therein, of a bed plate seated on the cross tie and provided 80 with upstanding abutments and having openings registering with the recesses in the cross tie, socket members seated in the recesses in the cross tie, bolt extending through the cross tie and engaging the socket members, rail clamping members having angular faces for engagement with the abutments and provided with depending angular portions extending through the openings in the bed plate and into the socket members, and 85 screw caps engaging the threads on the bolts and bearing against the rail clamping members.

7. The combination with a cross tie having spaced recesses formed therein, of a bed plate seated on the cross tie and provided 90 with spaced upstanding abutments, spaced openings registering with the recesses in the cross tie, socket members seated in the recesses in the cross tie and having angular 95 walls, bolts extending through the cross tie, nuts threaded on the bolts and bearing against the socket members, rail clamping members having angular faces for engagement with the abutments and provided 100 with depending angular portions extending through the openings in the bed plate and fitting the angular walls of the socket members, and screw caps engaging the threads 105 on the bolts and bearing against the rail clamping members.

8. The combination with a cross tie having spaced recesses formed therein and disposed in staggered relation, of a bed plate seated on the cross tie and provided with 110 spaced upstanding abutments and having openings formed therein, the walls of which are angular and register with the recesses in the cross tie, socket members seated in the recesses in the cross tie and having angular faces, fastening devices extending 115 through the cross tie and engaging the socket members, rail clamping members having angular faces adapted to engage the abutments and provided with eccentrics having angular faces for engagement with the base flange of a rail, said rail clamping members being provided with depending angular portions extending through the openings 120 in the bed plate and fitting the angular walls 125 of the socket members.

of the socket members, and screw caps engaging the threads on the bolts and bearing against the rail clamping members.

9. A rail chair including a bed plate having upstanding abutments and provided with openings, the walls of which are angular, socket members co-acting with the bed plate, bolts engaging the socket members, rail clamping members having angular faces 10 engaging the abutments and provided with eccentric portions having angular faces for engagement with the base flange of a rail, said rail clamping members having depending angular portions adapted to fit within 15 the socket members, and screw caps engaging the threads on the bolts and bearing against the rail clamping members.
10. A rail chair including a bed plate having upstanding abutments and provided 20 with openings, the walls of which are angular, socket members co-acting with the bed plate and adapted to fit within a cross tie, and rail clamping members having angular faces for engagement with the abutments 25 and provided with depending angular portions extending through the openings in the bed plate and into the socket members for holding a rail in different positions of lateral and vertical adjustment with respect to the bed plate.
11. A rail chair including a bed plate having an upstanding abutment and provided with an opening, the wall of which is angular, and a rail clamping member engaging said abutment and provided with a 30
- 35

depending angular portion fitting within and movable to different positions around the angular wall of the opening in the bed plate.

12. A rail chair including a bed plate 40 having an upstanding abutment and provided with an opening, the wall of which is angular, a socket member arranged beneath the opening in the bed plate and adapted to fit into a cross tie, and a rail clamping member 45 having angular faces for contact with the abutment and provided with an eccentric having angular faces for contact with the base flange of a rail, said rail clamping member being provided with a depending angular portion extending through the opening in the bed plate and into the socket member, the rail clamping member being movable to different positions around the angular wall of the opening in the bed plate for holding the rail in different positions of lateral and vertical adjustment with respect to the bed plate.

13. A rail clamping member comprising a body having an opening therethrough for 60 the reception of a fastening device and provided with a circumferential flange, the lower face of which is inclined downwardly, said body beneath the flange being provided with an eccentric portion and a depending 65 tubular extension, the exterior wall of which is formed with a series of angular faces.

In testimony whereof I affix my signature.

AUGUST G. LIEBMANN. [L.S.]
